FLUID PRESSURE CONTROL MECHANISM
FOR AIRPLANE DEICERSWilfred A. Eaton, Elyria, Ohio, assignor to Bé-
dix-Westinghouse Automotive Air Brake Com-
pany, Elyria, Ohio, a corporation of Delaware

Application April 30, 1943, Serial No. 485,227

9 Claims. (Cl. 244—134)

1

This invention relates to control mechanism for airplanes and more particularly to fluid pressure means for controlling the deicing mechanism of an airplane.

It has previously been proposed to employ inflatable deicer boots on the wings of airplanes in order to remove ice formations dangerous to the operation of the airplanes, but in many of the systems proposed, it has been necessary for the pilot to manually control the deicing mechanism, and in some cases the pilot has neglected to set the deicing mechanism in operation in time to prevent ice accumulations sufficient to interfere with the safe operation of the airplane, and it is accordingly one of the objects of the present invention to overcome these difficulties.

A further object of the invention is to provide means for automatically indicating to the pilot the formation of ice on the wings of the airplane in sufficient quantity to interfere with the safe operation of the airplane.

Yet another object of the invention is to provide means controlled by the formation of ice at one point on the airplane for automatically inflating or deflating the deicers to remove ice accumulations at another point on the wings of the airplane.

Still another object of the invention is to provide means for preventing formations of ice on the wings of the airplane from interfering with the operation of the automatic deicer control means.

A further object of the invention is to provide automatic mechanism for controlling the operation of the deicers, which may be readily applied to deicers of the existing type.

These and other objects of the invention will be more readily apparent when taken into consideration with the accompanying drawings, wherein two embodiments of the invention are illustrated. It is to be expressly understood, however, that the drawings are employed for the purpose of illustration only, and are not designed as a definition of the limits of the invention, reference being had for this purpose to the appended claims.

In the drawings, wherein similar reference numerals are used for similar parts throughout the several views,

Fig. 1 is illustrative of an automatic deicer mechanism constructed in accordance with the principles of the present invention;

Fig. 2 is a view in section of one portion of the system; and

2

Fig. 3 is a view, partially in section, of another embodiment of the invention.

Referring more particularly to Fig. 1, the deicer mechanism is illustrated as applied to an airplane, not shown, having a wing 4 provided with an inflatable deicer boot 5 preferably positioned adjacent the leading edge of the wing, fluid pressure for inflating the boot being supplied thereto from a suitable fluid pressure reservoir 6 through the medium of conduits 7, 7a, 8, 9 and 10 interconnected therebetween, the supply of fluid pressure from the reservoir to the conduit 7a and to the other conduits being under the control of the pilot by means of a three-way valve 11, of conventional construction, and adapted with the operating handle 12 in one position to permit the flow of fluid pressure from the reservoir through the conduit 7, and with the handle in another position to prevent the flow of fluid pressure therethrough and to connect the conduit 7a with an exhaust conduit 13 carried by the valve. A feed valve 14, likewise of well-known construction, serves to supply fluid pressure from the conduit 8 to the conduit 9 at a reduced pressure which may be selected by adjustment of an adjusting screw 15, while communication between conduits 9 and 10 and between the conduit 10 and atmosphere is controlled by a valve mechanism 16 as shown.

30 The valve mechanism 16 is of the fluid pressure operated type, having a casing 17 provided with an inlet chamber 18 and an outlet chamber 19 separated by a ported partition 20, communication between these chambers being controlled by means of an inlet valve 21 positioned in the inlet chamber and provided with a stem 22 extending upward through the ported partition into the outlet chamber and provided at its upper end with an exhaust valve 23, the valve assembly 35 thus formed being normally maintained in the position shown to prevent communication between the two chambers through the ported partition by means of a spring 24 interposed between the lower side of the exhaust valve and the upper face of the partition. The outlet chamber 19 is connected with the interior of the deicer boot 5 through the medium of conduit 10, while the inlet chamber 18 is connected with the reservoir 6 through conduit 9, feed valve 14, conduit 50 8, conduit 7a, valve 11 and conduit 7. The upper portion of the outlet chamber is closed by means of a partition 25 provided with a bore 26 and a valve operating plunger 27 slidably mounted thereon, the partition 25 thus forming, in connection with the casing, an exhaust chamber 23

having an atmospheric port 29. With the plunger 27 in the position shown, the outlet chamber 19 is connected with the exhaust chamber 28 through the medium of a port 30 formed in the valve operating element. The upper end of the exhaust chamber 28 is closed by means of a flexible diaphragm 31 suitably attached at its center to the valve operating plunger 27, and forming in connection with a closure member 32, bolted to the casing as shown, a control chamber 33, the valve operating plunger and diaphragm being normally maintained in the position shown by means of a spring 34 interposed between the upper face of the partition 27 and the lower face of the diaphragm 31. Leakage between the chambers 19 and 28 through the bore 26 is prevented by means of a suitable seal 35 positioned in the bore. It will thus be seen that with the valve in the position shown the interior of the deicer boot is in communication with the atmosphere through the conduit 10, outlet chamber 19, port 30, exhaust chamber 28 and exhaust port 29, while on downward movement of the valve operating plunger in response to application of fluid pressure to the chamber 33, the valve operating element first abuts the upper end of the exhaust valve to close the port 30, and subsequently moves the inlet valve to open position against the spring 24 to permit communication between chambers 18 and 19 to supply fluid pressure to the interior of the deicer boot at a pressure determined by the setting of the feed valve 14, this feed valve being so constituted as to maintain the desired pressure in the inlet chamber 18 of the valve 16 at all times, regardless of the pressure obtaining in the supply reservoir 6.

Novel means are provided for controlling the operation of the valve 16 including a detector element 36, preferably mounted at the leading edge of the wing as shown and comprising a body portion 37 having a bore 38 therethrough, the outer end of the bore being closed by means of a plate 39 suitably clamped to the outer end of the body 37 by means of a clamping plate 40, the plate 39 being provided with a restricted passage 41 for permitting communication between the passage 38 and atmosphere. As indicated on the drawing the body 37 may be suitably clamped to the leading edge of the wing by means of nuts 42 and 43. The bore 38 is provided with a supply conduit 44 and the latter is connected with the conduit 7a by means of a fluid-flow restricting device 45, this device having a casing 46 divided into inlet and outlet chambers 47 and 48 respectively, by means of a partition 49 formed at the casing, this partition being provided with a port 50 connecting the two chambers and preferably of smaller capacity than the orifice 41 located in the plate 39 of the detector 36.

It will be apparent from the foregoing that with the valve 16 so positioned as to permit communication between conduits 7 and 7a, fluid under pressure will constantly be supplied to the orifice 41 through the restricted passage 50 and conduit 44, and in view of the fact that the passage 50 is relatively small and is also smaller than the orifice 41, it will be seen that a relatively small flow of fluid will escape to atmosphere through the orifice 41 at all times, without, however, appreciably increasing the pressure in the conduit 44 above that of the surrounding atmosphere. It is also preferable to so adjust the size of passage 50 in relation to the capacity of the fluid pressure

source 6, as to prevent unnecessary depletion of the fluid pressure in the reservoir.

When the airplane is flying under atmospheric conditions conducive to the formation of ice on the wings, it will be understood that ice will also tend to form adjacent the orifice 41, and in the event the ice formation continues, the orifice will become closed, with the result that the pressure in the conduit 44 and the passage 38 will increase to the same value as that in the supply reservoir 6, this pressure thus providing an automatic indication of the formation of ice on the leading edge of the wing and adjacent the orifice. In order that the variations in pressure in the conduit 44 may be utilized to control the operation of the deicer mechanism, a governor mechanism 51, of well-known construction is provided, the governor being connected with the conduit 44 by means of a conduit 52, and with the control chamber 33 of the valve 16 by means of a conduit 53. It will be understood by those skilled in the art, that a governor of the above type will serve when the pressure in the conduit 44 is below a predetermined value to establish a connection between conduit 53 and atmosphere, and will serve when the pressure in the conduit 44 exceeds a predetermined value to establish a connection between conduits 52 and 53 and disestablish the connection between conduit 53 and atmosphere, a subsequent predetermined reduction of pressure in the conduit 44 serving to again dis-establish the connection between conduits 52 and 53 and re-establish the connection between the conduit 53 and atmosphere to exhaust fluid under pressure from the conduit 53. Thus on closing of the orifice 41 by formation of ice adjacent thereto, the pressure in the conduit 44 will increase to a value sufficient to actuate the governor to dis-establish the connection between conduit 53 and atmosphere and supply fluid pressure from the conduit 44 to the control chamber 33 of the valve 16 through conduit 52, the governor 51 and conduit 53, the pressure supplied to the valve 16 serving to move the diaphragm and valve operating element downward to close the exhaust valve and open the intake valve 21 to admit fluid pressure to the deicer boot 5 to inflate the latter and destroy any ice formations thereon. At the same time, the increase in pressure in the conduit 44 and in the passage 38, acting against the ice closing the orifice 41, will eventually be sufficient to break the ice, thus permitting the conduit 44 to again exhaust to atmosphere with resultant operation of the governor 51 to exhaust the chamber 33 of the valve 16 and to permit the latter to exhaust fluid from the deicer boot 5. When this action occurs, it will be clear that in the event the atmospheric conditions are still conducive to the formation of ice, the orifice 41 will again be closed by the ice formation and the above described cycle of operation will be repeated.

It is contemplated, however, that under certain conditions of operation, the pressure built up in the conduit 44 and in the passage 38 will be insufficient to expel the ice from the orifice 41, and consequently, a modified form of detector is illustrated in Fig. 2 of the drawings, the detector being identical in construction with the detector shown in Fig. 1 except for the construction of the orifice plate 39, which is made of flexible material. Although the entire right face of the flexible member 39 is subjected to the pressure in the enlarged end of the bore 38, flexing of the member 39 to the right under the action of the slip stream is prevented by means of stops 54

formed on the body 37, the purpose of this arrangement being to prevent flexing of the member under the action of the slip stream to remove ice formations therefrom. The flexible member is free to flex to the left, however, and it will be understood that as the pressure in the passage 38 increases due to closing of the orifice 41 by the formations of ice adjacent thereto, a pressure will eventually be reached in the passage 38 which will flex the member sufficiently to remove ice formations therefrom, to again open the orifice and to permit fluid pressure to escape therethrough. Thus it will be seen that, in the event the orifice tends to close when the construction in Fig. 1 is used, resulting in the deicer mechanism becoming inoperative, this condition will be readily overcome by utilizing the construction shown in Fig. 2.

Referring to Fig. 3, a modified deicer control is illustrated, more particularly adapted to use in connection with the control of deicer mechanism of the type already in common use. Here again a reservoir 6 is utilized as a source of fluid pressure and is adapted through the medium of conduit 7 to be connected with a detector 36, of the type shown in Fig. 1, through a conduit 44, this conduit being provided with a restricted passage or choke 50, corresponding to the choke illustrated in Fig. 1, and preferably of smaller capacity than the orifice 41 in the detector element. As heretofore explained, means are thus provided for constantly exhausting fluid to atmosphere through the orifice 41, closing of the orifice as a result of formation of ice adjacent thereto resulting in an increase in pressure in the conduit 44 between the choke 50 and the orifice 41. In this embodiment of the invention the pressure variations in the conduit 44 are utilized to actuate indicating means for advising the pilot of the formation of ice on the wings of the airplane, one of these means being a pressure gauge 55, connected to the conduit 44 by means of a conduit 56, and the other being an indicator light 57, adapted to be energized or de-energized by means of a pressure operated switch 58, preferably constructed in accordance with the principles set forth in the patent to Stephen Johnson, Jr., and Stephen Vorech, No. 1,925,762, dated September 5, 1933, and connected with the conduit 56 by means of a conduit 59. The switch is provided with terminals 60 and 61, and it will be understood that when the pressure to the conduit exceeds a predetermined value, the switch will be operative to establish an electrical connection between the terminals. One pole of a battery 62 is connected with the terminal 61 by means of a wire 63, the other terminal of the battery being connected to one side of the lamp filament by means of a wire 64 and the other side of the filament being connected to the terminal 60 by means of a wire 65. The switch 58 is preferably so adjusted as to establish a connection between the terminals 60 and 61 when the pressure in the conduit 44 rises sufficiently to indicate a formation of ice on the wing or adjacent the orifice 41 sufficient to interfere with safe operation of the airplane, and it will be understood from the foregoing that the apparatus heretofore described will serve, either through observation of the gauge 55 or the indicator 57, to advise the pilot of any such condition in order that he may operate the manual controls of the deicer mechanism to start operation of the deicer in the event the airplane is so equipped.

At the present time airplanes are often 75

equipped with deicer mechanisms wherein the inflation and deflation of the deicer boot is controlled by means of a distributor driven by an electric motor for inflating and deflating the boot 5 at predetermined intervals, and such a mechanism is illustrated in Fig. 3, as including a slow speed electric motor 65 having a distributor valve 66 driven thereby and adapted to alternately establish a connection between an outlet conduit 67 leading to the deicer boot and an exhaust port 68, and between the outlet conduit 67 and a supply conduit 69 connected with a suitable source of fluid pressure, such as the reservoir 6. A deicer mechanism of this type can be readily controlled by the control mechanism heretofore described, the electric motor being provided with terminals 70 and 71, the terminal 70 being connected to the left end of the battery 62 by means of a wire 72, and the terminal 71 being connected to the wire 65 by means of a wire 73. Thus, on operation of the switch 58 to establish a connection between terminals 60 and 61 in response to an increase in pressure in the conduit 44, it will be understood that the motor 65 will be energized by the battery to drive the distributor valve 66 and to alternately inflate and deflate the boot of the deicer to remove ice formations on the wing of the airplane. In like manner, when any other type of deicer mechanism is utilized, the mechanism can be readily controlled through the medium of the mechanism described, which serves to automatically indicate to the pilot the formation of ice on the wings of the airplane, and at the same time to automatically render the deicer mechanism effective to remove this ice from the wing.

Although the invention has been illustrated and described herein with considerable particularity, it is to be understood that the same is not limited to the form shown but may receive a variety of mechanical expressions, as will readily appear to those skilled in the art. Reference will, therefore, be had to the appended claims for a definition of the limits of the invention.

What is claimed is:

1. The combination with an airfoil having an inflatable device associated therewith for breaking formations of ice thereon, of an orifice positioned adjacent said airfoil and adapted to be restricted by the formation of ice adjacent thereto, a source of fluid pressure, a connection between said source and orifice, means associated with said connection for normally supplying fluid to said connection and orifice at a limited pressure and for increasing said pressure on restriction of said orifice by the formation of ice adjacent thereto and for finally further increasing said pressure to a value sufficient to remove the ice adjacent the orifice, a connection between said source and device, and means associated with said last named connection and operable in response to the initial increase in pressure in said first named connection due to the restriction of said orifice for supplying fluid from said source to said device.

2. The combination with an airfoil having an inflatable device associated therewith for breaking formations of ice thereon, of an orifice positioned adjacent said airfoil and adapted to be restricted by the formation of ice adjacent thereto, means operable on restriction of said orifice for supplying fluid thereto at an increasing pressure which finally reaches a value sufficient to remove said ice formation, and means responsive to the increasing pressure of fluid supplied to said

orifice for supplying fluid under pressure to said device for inflating the latter and breaking the formation of ice on said airfoil.

3. The combination with an airfoil having an inflatable and deflatable device associated therewith for breaking formations of ice thereon, of an orifice positioned adjacent said airfoil and adapted to be restricted by the formation of ice adjacent thereto, means for normally supplying fluid to said orifice at a relatively low pressure and for increasing said pressure on restriction of said orifice by the formation of ice adjacent thereto and for finally further increasing said pressure to a value sufficient for removing said ice formation, and fluid pressure control means responsive to the initial increase in the pressure of fluid supplied to said orifice for correspondingly controlling the inflation and deflation of said device.

4. The combination with an airfoil having an inflatable device associated therewith for breaking formations of ice thereon, of a flexible element positioned adjacent said airfoil and subjected to the slip stream of the airplane, means for supplying fluid under pressure to said element, an orifice formed in said element for normally exhausting the fluid supplied to said element and operable on the formation of ice adjacent thereto for increasing the pressure of fluid supplied to said element for moving said element and removing the formation of ice adjacent said orifice, and means responsive to the pressure supplied to said element for controlling the degree of inflation of said device.

5. The combination with inflatable ice removing means for an airfoil and means including a motor for alternately inflating and deflating said means, of means for controlling the operation of said motor including a conduit, means for supplying fluid under pressure to said conduit, an orifice in said conduit for exhausting fluid from said conduit and operable on restriction thereof by the formation of ice adjacent thereto for preventing the exhaust of fluid from said conduit and increasing the pressure therein, means associated with said conduit and operable in response to said increase in pressure for energizing said motor, and means responsive to the pressure of said fluid for breaking formations of ice adjacent said orifice.

6. Ice removing means for an airfoil including an inflatable member associated with said airfoil, a source of compressed fluid, means including a valve operable for connecting said source and member for inflating the latter and operable for exhausting fluid from said member to deflate the latter, and means including an orifice having a connection with the source of fluid and subjected to the slip stream of the airplane for controlling the operation of said valve.

7. Ice removing means for a body adapted for movement in a fluid medium including a power operated element movable with respect to said

body for removing ice formations thereon, a source of compressed fluid, and means for controlling the energization of said power operated element including an orifice subjected to the flow of fluid medium by said body, means for connecting said source and orifice for supplying fluid to the latter, means operable on restriction of said orifice by formation of ice adjacent thereto for energizing said power operated element, and means responsive to the pressure of the fluid in the connecting means for breaking formations of ice adjacent said orifice.

8. Deicer mechanism for a body subjected to ice formation including a power operated device movable with respect thereto for breaking said ice formation, an orifice subject to said ice formation, means including a source of compressed fluid for establishing a flow of fluid through said orifice, means operable on restriction of said flow for energizing said power operated device, and means responsive to the pressure of said fluid for breaking formations of ice adjacent said orifice.

9. Ice removing means for a body adapted for movement in a fluid medium including an inflatable and deflatable device associated therewith and a source of compressed fluid, and means for effecting a cyclic control of the inflation and deflation of said device to effect removal of ice from said body including pressure responsive means for connecting said source and device for inflating the latter and for exhausting fluid pressure from the device to deflate the latter, an orifice subjected to said fluid medium and subjected to ice formation to restrict said orifice, connecting means between said source and orifice for supplying fluid to said orifice at a low pressure when said orifice is unrestricted and for supplying fluid to said orifice at a pressure sufficient to remove ice formations therefrom when the orifice is restricted by said ice formations, and means for connecting said connecting means and pressure responsive means whereby the latter is subjected to variations of pressure in said connecting means in accordance with variations in the restriction of said orifice.
